CAR STORAGE GARAGE

Alexander S. Elliott, Toronto, Ontario, Canada

Application April 4, 1946, Serial No. 659,618

2 Claims. (Cl. 20—1.13)

1

This invention relates to improvements in car storage garages.

Many proposals have been made in respect to garages for the storage of a substantial number of cars. Proposals of this kind generally embody a plurality of storage floors and inclined runways running from floor to floor and which usually are of substantial width in order to permit the passage of cars going up and going down, while such runways are usually made substantially in the form of a spiral so that the car travels in a circuitous route. This means that the space in a storage building allotted to runways must be double that which would be necessary if one single straight runway were possible, and where provision is made so that cars may use the same runway both going up and going down the width of the runways must be four times that of a single runway such as referred to for the purposes of comparison. Consequently, very substantial space is taken up in such structures merely for runway purposes and consequently storage space available is reduced substantially in comparison to a structure which employed a single straight runway serving various floors of the building.

The present invention avoids the disadvantages of the prior art, such as generally referred to above, and provides a structure which may employ a single straight runway designed to lead cars to upper levels and a single straight runway either above or below the first mentioned runway and leading cars downwardly from the upper level. Alternatively, a portion of the runways adjacent to the exit may be offset from the other to provide separate entrance and exit as will later appear.

In prior garage constructions, it has been necessary to leave a substantial open space on the several storage floors in order to maneuver the cars into a position for parking in a manner that they may be readily taken out when desired. According to the present invention, such space is materially reduced while cars parked on the various levels are readily accessible and may be easily taken out when desired.

It is therefore an object of the present invention to provide a storage garage for cars which by reason of material savings in space will store a large number of cars and a substantially greater number than is possible in storage buildings of equal size constructed according to proposals of the prior art.

A further object of the invention is to provide a particularly novel type of runway wherein the

2

inlet runway and the outlet runway are disposed one above the other and may be provided as straight inclined runways leading to the various storage floors provided and permitting the location of said runways merely at one end of the building if desired.

A further object of the present invention is to provide a car storage structure wherein the free floor space provided on the various storage floors is reduced to a minimum while providing for the easy maneuvering of cars on said space as they are being parked in readily accessible location.

The invention will be fully understood by reference to the following detailed specification taken in conjunctions with the accompanying drawings.

In the drawings,

Figure 1 is a perspective illustration of a rectangular garage building employing entrances and exits to upper and lower runways according to the present invention.

Fig. 2 is a fragmentary perspective illustration of one corner of the storage garage at the entrance and exit to and from the upper level showing the manner in which part of the upper runway is offset to permit separate entrance and exit in respect to the upper and lower runway.

Fig. 3 is a fragmentary transverse section taken through the section of the building shown in Fig. 2.

Fig. 4 is a fragmentary schematic perspective of a manner in which the cars may pass between upper storage floors and the inclined runways.

Referring to the drawings, A indicates a car storage building according to the present invention having a lower storage floor 10 and upper storage floors 11 and 11a. Entrance and exit to and from the upper storage floors 11 and 11a is obtained through the entrance door opening 12 and the exit door opening 13 which are disposed adjacent to one another. The exit door 13 communicates with the upper inclined runway 14 while entrance doorway 12 communicates with the lower inclined runway 15. These runways are straight runways, one disposed directly above the other, and of a width practicably to accommodate the passage of the width of a car with necessary allowance for proper clearance. Since the entrance doorway 12 is disposed to one side of the exit doorway 13, runway 14 is offset as at 16 when it begins to approach the exit 13. Consequently, initially the runway 14 is beside and parallel to the entrance runway 15, and accessible through the exit doorway 13, until it swings

to the left as shown in Figures 2 and 3 to overlie the entrance runway 15 throughout the remainder of its extent.

From the entrance doorway 12 access is obtained to the lower runway 15 by means of a downwardly inclined leadway 18 which slopes down to a lower or starting level 19 from which the lower runway inclines upwardly substantially parallel to the upper runway 14 throughout the remainder of its extent. Thus, by leading the cars downwardly on the slope 18 from entrance doorway 12 to the lower level 19 this provides for a spacing between the upper runway 14 and the lower runway 15 practicably to accommodate the height of a car and permitting these runways to run in the same line, one above the other, substantially parallel to one another, saving substantial space in the building. Moreover, the offset portion of the runway 14, offset as at 16, will not in effect take up greater space in the building to the detriment of storage or the like since it is, of course, necessary to provide for office space as well as other space such as storage of parts, etcetera, and the offset portion of the runway, while taking up some space which might be used for storage, on the other hand provides sufficient space for the location of these important complements of a storage garage, which may include elevators, all located in the space 17.

As previously indicated, the runways 14 and 15 are chosen of a width practicably to accommodate the width of a car so that these runways therefore take up a minimum of space in the building. Preferably, it is proposed to cause the marginal portions of the floors of the runways to merge with the side walls thereof in a graduated curve as indicated at 20 in Figure 2. Therefore, the marginal portions will serve to guide the wheels of the cars if they were to be directed towards the outer sides of the runway to obviate, in any instance, danger of scraping the side walls. They will tend to guide the car normally through the extent of the runway.

The upper and lower runways 14 and 15 are designed to communicate with suitable exits and entrances respectively to the upper storage floors 11 and 11a. Assuming a car is driven through the entrance doorway 12 it will pass down the leadway 18 to the starting level 19 then up the runway 15 and may be stored on the first upper floor 11 by driving the car through the doorway 43 which communicates with the runway 15 as shown in Figure 4. A suitable graduated ramp 44 may be employed in conjunction with the doorway 43 to permit the car to be driven onto the level of floor 11, having regard to the upward slope of the runway 15. The car is then maneuvered on the floor and placed in its proper location. When it is desired to remove the car from the building, it is driven along the floor 11 to the exit 45 and over the graduated ramp 46 to the runway 14 with which the exit 45 communicates. Exactly the same arrangement occurs in connection with the second floor 11a, wherein the inlet doorway 47 communicates with the lower runway 15 and the exit doorway 48 communicates with the upper runway 14. Obviously the same arrangement may be employed with the third and fourth floors, the only limitation being the length of the building which determines the length of the runways 14 and 15, and the height to which they may extend. Alternatively, of course, a second pair of runways in addition to runways 14 and 15 might be

employed disposed above the latter, entrance and exit thereto being gained from floor 11a, if it were desired to produce a building of substantial height with a large number of storage floors while restricting the length of the building. However, in view of the fact that the proposal of the present invention will permit the storage of a much larger number of cars within a space smaller than that of the average storage garage employing runways of double width for inlet and exit of cars and circling through the building, as referred to in the first of this application, it would not apparently be necessary to employ a large number of floors.

As a comparison between a storage building now employed and using runways of double width, for inlet and exit, circling through the buildings, the following general dimensions are given of such a known structure, compared to one of the present invention. The known structure has a length of 207 feet and a width of 105 feet, employing four stories above the ground and two floors below the ground, providing eleven storage levels. This provides for the parking of 514 cars. The runways are approximately 30 feet in width to permit the passage of two cars going up and down and also to permit the necessary room for passing on the turns, at which point, substantial difficulty is experienced even with runways of this width. The circling runway from floor to floor results in a runway requiring substantially one mile of travel to go from street level to the farthest point on the upper level and then back down to the street level.

As compared to this known structure of conventional design, a structure 180 feet long and 72 feet in width (33 feet less than the conventional, as described above) and employing only two stories which are above ground will park 448 cars or, in other words, will more than double the capacity of the conventional building described when taking into consideration the number of stories employed, as well as an area substantially less, while the complete runway travel to the top floor and back would be not more than 800 feet. These advantages are achieved by the novel arrangement of runway according to the present invention and, as well, the reduction in free maneuvering space on the floors compared to that required in a flat floor.

The structure of the storage garage of the present invention can follow very conventional lines and is preferably made up of a superstructure of girders and trusses which may be produced in standard sections and bolted together such that the inner structural parts of the building can be dismantled and removed in sections to be used in another location if for any reason it was necessary to abandon the original site. Accordingly, the site of the building may be changed with comparatively small loss, i. e., the loss of the outer shell or those parts of which could not be employed in the new building. This is impossible in a building of the conventional design referred to, employing runways circling through the buildings.

The foregoing will illustrate that I am able to provide a car storage garage which will house a substantially large number of cars comparatively to the space occupied and a substantially larger number of cars than conventional structures employing large areas.

What I claim as my invention is:

1. In a car storage garage adapted to serve a street or like predetermined level, the combina-

tion of: a plurality of car storage floors horizontally disposed but displaced vertically from the predetermined level and extending the entire length of the garage; two inclined parallel spaced apart runways serving all traffic for all car storage floors, extending from said predetermined level and disposed directly one above the other a distance sufficient only to accommodate free passage of a car with slight additional headroom on the lower runway of the two, said runways being disposed in the direction of the length dimension of the garage and serving traffic moving in opposite directions to and from said storage floors but each handling traffic in one direction only; means communicating each of said runways to each of said car storage floors; an opening in said garage through which a car may pass and located directly at the predetermined level; an inwardly and upwardly inclined leadway extending from said opening to said upper runway; an additional opening in said garage located at said predetermined level directly adjacent said first mentioned opening; and an additional leadway extending independently from said additional opening to said lower runway; said first mentioned leadway being offset with respect to said second mentioned leadway to provide clearance for vehicles on said second mentioned leadway.

2. A car storage garage as claimed in claim 1, wherein the leadway of the upper runway lies in the plane of the runway, and the leadway of the lower runway is inclined downwardly from said predetermined level and then proceeds at a level below said predetermined level to a line of junction with said lower runway.
